UNITED STATES PATENT OFFICE.

DONALD S. BARROWS, OF ROCHESTER, NEW YORK.

SIDE FRAME.

Application filed August 15, 1925. Serial No. 50,441.

This invention relates to side frames for railway car trucks and more particularly to cast frames in which some of the junctions between members are relatively flexible.

5 The principal object of my invention, generally considered, is the provision of a cast frame for railway car trucks in which a relatively rigid structure is provided over the journal boxes for taking care of secondary 10 stresses and rigidly uniting the ends of the compression and tension members, said compression and tension members, at intermediate portions thereof, being reduced in depth and spaced by bolster columns with the provision of relatively flexible junctions 15 between said members and bolster columns.

An object of my invention is the provision of a cast side frame for railway trucks in which the junctions between the compression 20 and tension members are made relatively rigid and an elliptic structure is provided adjacent each end of the frame designed to resist local concentrated loads from the journal boxes, the secondary stresses which may 25 result from actual non-intersection of the neutral axes of the members, and those which arise from a tendency toward relative angular movement under load between the tension and compression members.

30 Another object of my invention is the provision of a side frame for railway car trucks in which the compression member is so formed that it is relatively shallow at the center thereof, is designed to flex to a maximum degree at that point, and provided with 35 bolster columns which are relatively shallow so that they may accommodate themselves to flexing movement of the compression member.

40 Another object of my invention is the provision of a side frame for railway cars in which the compression and tension members are rigidly connected at their ends and spaced at intermediate portions thereof by 45 bolster columns, the lower ends of said bolster columns being united to form a spring plank seat which rests on the central portion of the tension member, the tension member being formed relatively deep at its ends and 50 decreasing in depth until it is relatively flexible where it passes under the bolster columns, said tension member being divided adjacent said bolster columns so that portions 55 of the spring plank seat pass therethrough, and so flexible adjacent its junction there-

with that secondary stresses at such junction are eliminated.

Other objects and advantages of the invention relating to the particular arrangement and combination of the various parts 60 will become apparent as the description proceeds.

Referring to the drawings illustrating my invention, the scope whereof is pointed out in the claims:

65 Figure 1 is a side elevation of an embodiment of my improved side frame.

Figure 2 is a plan view of the structure illustrated in Figure 1, shown partly in section on the line 2—2 of Figure 1, and partly 70 broken away.

Figure 3 is a sectional view on the line 3—3 of Figure 1.

Figure 4 is a transverse section through one of the bolster columns on the line 4—4 75 of Figure 1.

Figures 5 and 6 are transverse sections of the compression member on the correspondingly numbered lines of Figure 1.

Figure 7 is a sectional view on the line 80 7—7 of Figure 1.

Figure 8 is a detail sectional view on the line 8—8 of Figure 1.

Figures 9 and 10 are detail sectional views 85 on the correspondingly numbered lines of Figure 1.

Figure 11 is a partial side elevation corresponding to Figure 1, but showing a modification.

Referring to the drawings in detail, in 90 which similar reference characters designate like parts, a preferred embodiment of my side frame 1 is illustrated and comprises a compression member 2 and a tension member 3, said compression and tension members 95 being rigidly united at their ends and to rigid structures 4 adapted to extend over and embrace the journal boxes, not shown. These rigid structures 4, at each end of the frame, are formed generally elliptical or 100 elongated in outline with upright web portions 5, lower flange portions 6, and upper flange portions 7, in the present embodiment.

The flange portions 6 and 7 are curved over and around the adjacent journal box 105 and united at their ends, forming a structure somewhat resembling the head of a wrench, the jaws of which embrace the corresponding journal box. Bracing webs 8 may be provided between the flanges 6 and 7 110

of the elliptical structure 4, said webs preferably diverging outwardly from the lower flange 6 and certain of said webs being formed as continuations of flange portions 5 of the compression and tension members. For instance, the compression member 2 is preferably formed as an I section adjacent its ends and therefore comprises an upright web portion 9 and upper and lower flanges 10 and 11, respectively. The tension member is likewise formed as an I section adjacent its ends and comprises an upright web portion 12 and upper and lower flange portions 13 and 14, respectively. The flange 15 portions 11 and 14 of the compression and tension members are preferably continued, as illustrated, past the outer flange 7 of the elliptical structure 4 to form the adjacent web members.

20 The inner portions of the compression and tension members are decreased in depth to provide greater flexibility, the compression member also changing in shape in the present embodiment from an I section to a channel section and the intermediate portions of the members are spaced by bolster columns 15. The change in the cross-section of the compression member from I to channel section is accomplished gradually, preferably over the 25 bolster columns 15 by bifurcating the web 9 and flaring the portions thereof outwardly to form the depending flanges 16 and 17 of the channel portion of the compression member. The upper flange 10 of the I section of the compression member is continued to form the web portion 18 of the channel section. The lower flange 11 of the compression member is bifurcated along with the web 9 thereof and continued as beading 19 30 on the lower edges of the depending flanges 16 and 17.

40 The tension member 2 is decreased in depth toward its center as it approaches the bolster columns 15 and bifurcated adjacent 45 its junction with said bolster columns to permit the lower portions thereof to extend below and between the divided portions of said tension member. At its junction with the bolster columns 15, the tension member 50 3 is so shallow in depth or flat that angular motion therebetween is permissible without a substantial increase in secondary stresses. In other words, a substantially non-rigid or 55 articulated union is provided at the junction between the tension and bolster column members. Said tension member 3 finally merges with depending flanges 20 from the spring seat portion 21 which connects the lower ends of the bolster columns 15, as illustrated particularly in Figure 3.

60 The spring seating or spring plank portion 21 preferably comprises a substantially horizontal web portion 22 formed with a central depending flange or web portion 23 65 in addition to the flange portions 20 which

join with the tension member 3. The lower edge of the flange portion 23 is preferably ribbed or beaded at 24. The web 22 is formed relatively wide so as to accommodate the bolster springs. The portions thereof 70 which extend beyond the flanges 20 are preferably braced by triangular web portions 25.

The bolster columns 15 are formed generally T-shape in cross-section and relatively shallow so as to accommodate themselves to 75 flexing of the compression member 2 to which they are united at their upper ends. The web 26 of said bolster columns has, at its inner edge, a relatively wide flange 27 serving as a bolster guide portion and said web 80 may have at its outer edges beading or outwardly extending ribs 28. The outer edge of the web 26 is preferably ribbed or beaded, as indicated at 29, curved outwardly and downwardly adjacent the lower portion 85 of the bolster columns, and finally extended between the divided portion of the tension member 3 and continued as beading 24 on the downwardly extending flange 23 of the 90 spring seating portion 21.

The flange 27 of the bolster columns 15, at the lower portions thereof, is extended outwardly to increase the width of the window opening 30 to facilitate insertion and removal of said bolster, as is usual. The 95 width of the flange 27 is also preferably increased and finally curved inwardly and merged with the web 22, as illustrated particularly in Figure 1. The upper portion of the bolster columns, particularly the webs 100 26 thereof, are flared outwardly and connected with the lower portion of the compression member, the beading 29 thereon preferably curving around and merging with the lower flange 11 of the compression member. Although in the first embodiment illustrated the elliptical structures at the ends of the frame are shown merely adapted for connection with the journal boxes, I do not wish to be restricted to such a construction because, if desired, journal boxes may be 105 formed integral therewith, as shown in Figure 11.

Besides the bracing webs 8 formed on said elliptical structure 4, longitudinal bracing 115 webs 31 flaring from the edges of the webs 8, which are continued from the lower flange 11 of the compression member, may be provided merging at their outer portions with the adjacent webs 8. Triangular reinforcing ribs 32 may also be provided extending between angular portions of the inner flange 6 of the elliptical structure 4 and adapted to contact the adjacent portions of the journal boxes. Triangular webs or ribs 33 may also 120 be provided extending from the lower flange 14 of the tension member to the adjacent inner jaw portions 34 of the elliptical structure 4.

In the embodiment illustrated in Figure 130

11, the construction may be the same as that previously described, with a journal box 35 embraced by the rigid structure 4^a at each end of the frame and cast integral with the frame. The flange portions 6^a of these structures 4^a are preferably extended, as illustrated, to form the top and side walls of the boxes.

In view of the foregoing disclosure it will 10 be apparent that I have devised an improved side frame for railway car trucks which may be cast as an integral structure and yet provide relatively non-rigid or flexible joints between the tension member and bolster columns, as well as adjacent the center of the compression member. The compression and tension members are increased in depth and strength outwardly toward the points of application of the main forces, and preferably 20 rigidly united at their ends and to a rigid structure either formed around each journal box or adapted to embrace a journal box at each end of the frame. In other words, the cross-section area, and preferably the 25 height of one or both of said members or the webs thereof, is increased progressively from intermediate portions to or toward the ends of the members. In this way the forces at said ends, which are augmented by secondary 30 stresses at the junctions between the members are more efficiently taken care of. When in motion with the car on which the frame is applied, the stresses at the ends of the frame are further increased by dynamic 35 forces and impacts transmitted through the wheels and axles of the car.

The bolster columns are formed sufficiently strong but shallow enough to accommodate themselves to the flexure of the compression member adjacent the center thereof. The spring seating portion or spring plank seat is formed so that theoretically it is a segmental filler block resting in the catenary portion of the tension member but some of 45 its material is integrally connected with the tension member so that it carries some of the tensile stress in said member.

On account of this construction the compression and tension members act substantially as cantilevers rigidly anchored together over the journal boxes and pin-connected adjacent the bolster columns. Such a construction makes it possible to reduce the weight of cast side frames without sacrificing strength thereof because secondary 55 stresses, which are sometimes critical ones, are merely reduced at certain points.

The structure is after all a simple beam formed as an open truss carrying a central load distributed over practically the entire distance between the vertical ties and there is actually a pin connection at the points of reaction, which are the journal boxes. That is, under deflection the jaw ends or the in-

tegral journal boxes may rotate. The jaw 65 end and its partially elliptic reinforcement provides adequate sections to resist local bending moments which will actually be present through the practical non-intersection of the three force lines that are intended to intersect directly over the center of the axle. Incidentally, the construction resists a very definite calculable bending moment from a fore-and-aft load resulting from 70 brake applications or something similar. 75

Having thus described my invention, I claim:

1. A side frame comprising compression, tension and bolster column members, said compression and tension members being rigidly united at their ends, said bolster column members spacing intermediate portions of the compression and tension members and flexibly united with the tension member. 80

2. A side frame comprising compression 85 and tension members rigidly united at their ends and tapering in depth therefrom to intermediate portions thereof, bolster columns spacing intermediate portions of said compression and tension members, the tension 90 member being so reduced in depth adjacent its connection with said bolster columns that a relatively flexible junction therebetween is provided.

3. A truck side frame comprising compression, tension and bolster column members, said compression and tension members being rigidly united at their ends and spaced at intermediate portions by the bolster columns, said tension member being relatively deep 100 and rigid adjacent its junction with the compression member and relatively shallow and flexible adjacent its junction with the bolster columns. 105

4. A truck side frame comprising compression and tension members united at each end of the frame to a rigid structure adapted to extend over and embrace a journal box, intermediate portions of said members being relatively flexible. 110

5. A truck side frame comprising compression and tension members united at each end of the frame to an elliptic structure adapted to extend over and embrace a journal box and comprising curved outer and 115 inner bounding portions joined by approximately radially disposed webs.

6. A truck side frame comprising compression and tension members united at each end of the frame to an elliptic structure 120 adapted to extend over and embrace a journal box, said elliptic structure comprising an upright web and inner and outer flanges united at their ends.

7. A truck side frame comprising compression and tension members each formed with upright longitudinal webs and upper and lower flanges extending therealong, said 125

members being united at their ends to elliptic structures each adapted to extend over and embrace a journal box, said elliptic structures each being formed with an upright 5 longitudinal web and outer and inner flanges, the webs of the compression and tension members merging with the webs of said structures and the upper and lower flanges of said members merging respectively with 10 the outer and inner flanges of said structures.

8. A truck side frame comprising compression and tension members each formed with upright longitudinal webs and upper 15 and lower flanges extending therealong, said members being united at their ends to elliptic structures each adapted to extend over and embrace a journal box, said elliptic structures each being formed with an upright longitudinal web and outer and inner flanges, the webs of the compression and tension members merging with the webs of said structures and the upper and lower flanges of 20 said members merging respectively with the outer and inner flanges of said structures, said elliptic structures being provided with transverse bracing webs radiating from the inner to the outer flanges.

9. A truck side frame comprising compression and tension members each formed with upright longitudinal webs and upper and lower flanges extending therealong, said members being united at their ends to elliptic structures each adapted to extend over 30 and embrace a journal box, said elliptic structures each being formed with an upright longitudinal web and outer and inner flanges, the webs of the compression and tension members merging with the webs of said structures and the upper and lower flanges of 35 said members merging respectively with the outer and inner flanges of said structures, said elliptic structures being provided with transverse bracing webs radiating from the inner to the outer flanges, some of said webs being formed as continuations of compression and tension member flanges, whereby 40 said members and structures are more rigidly united.

50 10. A truck side frame comprising compression, tension and bolster column members, said compression member being rigidly connected to the tension member adjacent the ends thereof and decreasing in depth inwardly therefrom to permit a maximum flexing at the center thereof under load.

11. A truck side frame comprising compression, tension and bolster column members, said compression member being rigidly connected to the tension member adjacent the ends thereof and decreasing in depth inwardly therefrom to permit a maximum flexing at the center thereof under load, said bolster column members serving to space 60 intermediate portions of the compression 65

and tension members and being relatively shallow to accommodate themselves to flexing of the compression member.

12. A truck side frame comprising compression, tension and bolster column members, said compression and tension members being rigidly connected together adjacent the ends thereof and both decreasing in depth inwardly therefrom to permit maximum flexing at the intermediate portion 70 thereof, said bolster column members serving to space said intermediate portions, whereby said compression and tension members act substantially as cantilevers rigidly anchored together at the ends thereof and 75 pin-connected to the bolster columns.

13. A truck side frame comprising a compression member, a tension member and bolster columns, said bolster columns serving to space intermediate portions of said compression and tension members, and formed with a segmental filler block portion, between the lower portions of the bolster columns, resting on said tension member, with the formation of a flexible joint 80 therebetween.

14. A truck side frame comprising a compression member, a tension member and bolster columns, said bolster columns serving to space intermediate portions of said compression and tension members, said tension member extending below the bolster columns and bifurcated so that portions of 85 said columns can pass therethrough.

15. A truck side frame comprising a compression member, a tension member and bolster columns, said bolster columns serving to space intermediate portions of said compression and tension members, said tension member being decreased in depth, bifurcated, and extended below the bolster columns, the bifurcated portion embracing 100 downward extensions from the bolster columns.

16. A truck side frame comprising a compression member, a tension member and bolster columns, said bolster columns serving to space intermediate portions of said compression and tension member, said tension member being decreased in depth, bifurcated, and extended below the bolster columns, the bifurcated portion embracing downward extensions from the bolster columns and providing a flexible connection therewith, portions of the bolster columns 110 being so connected to the tension member 115 that they take part of the tensile stress therein.

17. A truck side frame comprising compression, tension and bolster column members, said compression and tension members being rigidly united at their ends, said bolster column members spacing intermediate portions of the compression and tension members, said compression member 125 130

- gradually changing from a channel of relatively small depth at intermediate portions thereof to a relatively deep I-beam adjacent the ends thereof.
- 5 18. A truck side frame comprising compression and tension members united at each end of the frame to a rigid structure embracing a journal box, said members decreasing in depth toward intermediate portions thereof to minimize secondary stresses.
- 10 19. A truck side frame comprising compression and tension members united at each end of the frame to an elliptic structure integral with and embracing a journal box,
- 15 said elliptic structure comprising an upright web and inner and outer flanges united at their ends.

20. A truck side frame comprising compression and tension members each formed with upright longitudinal webs and upper 20 and lower flanges extending therealong, said members being united at their ends to elliptic structures integral with and embracing a journal box, said elliptic structures each being formed with an upright longitudinal 25 web and outer and inner flanges, the webs of the compression and tension members merging with the webs of said structures and the upper and lower flanges of said members merging respectively with the 30 outer and inner flanges of said structures.

In testimony whereof I affix my signature.

DONALD S. BARROWS.
